UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 13,813, dated March 27, 1883.

Application filed January 23, 1883. Term of patent 3½ years.

To all whom it may concern:

Be it known that I, WINTHROP L. JACOBS, of East Orange, Essex county, New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The face of the design is traversed by a network of angular stems, bearing, variously disposed along their length and on short projecting stems, various flower and leaf figures, as

shown in the photograph. These figures have, as a characteristic common to most of them, marked serrated outlines. A, B, C, D, E, F, and G are the larger flower-like figures, and H, K, and L the larger leaf-like figures, all of which are clearly shown in the photograph. In the spaces between these larger figures are scattered along the connecting stems various smaller gem and leaf shapes, as shown. 25

I claim—

The design for a carpet, substantially as shown and described.

WINTHROP L. JACOBS.
